UNITED STATES PATENT OFFICE.

WILLIS W. HALE, OF CLEVELAND, OHIO.

ELECTRIC HEATER.

1,418,917.

Specification of Letters Patent. Patented June 6, 1922.

Application filed January 31, 1920, Serial No. 355,372. Renewed May 6, 1921. Serial No. 467,320.

To all whom it may concern:

Be it known that I, WILLIS W. HALE, a citizen of the United States, residing at Cleveland, in the county of Cuyahoga and State of Ohio, have invented certain new and useful Improvements in Electric Heaters, of which the following is a specification.

The present invention relates to an electric heater, and has for its object to provide a device of that character which embodies novel features of construction whereby a large surface heating area is provided and which also provides for a free circulation 15 of air around the heating surfaces, thereby enabling great efficiency to be obtained.

Further objects of the invention are to provide an electric heater which is formed of comparatively few and simple parts 20 which can be easily and quickly assembled without difficulty, which has a light and compact construction and can be easily transported or moved from place to place, and which will utilize the heating powers of 25 the electric current to the best possible advantage.

With these and other objects in view as will more fully appear as the description proceeds, the invention consists in certain 30 combinations and associations of the parts, the novel features thereof being pointed out in the appended claims.

For a full understanding of the invention reference is to be had to the following 35 description and accompanying drawings, in which:

Figure 1 is a top plan view of an electric heater constructed in accordance with the invention, one end of the heater being shown 40 in horizontal section and the supporting legs of the heater being broken away.

Figure 2 is a side elevation of the heater, portions being broken away and shown in section.

Figure 3 is a transverse sectional view on the line 3—3 of Figure 1.

Figure 4 is a plain view of the resistance element and one of the insulating thicknesses, showing the same before they have 50 been fitted between the reversely folded sheet metal thicknesses.

Figure 5 is an enlarged horizontal sec-

tional view through a few of the reversely folded sheet metal thicknesses between which the insulated resistance wire is positioned. 55

Corresponding and like parts are referred to in the following description and indicated in all of the views of the drawings by the same reference characters.

Referring to the drawings, which illustrate one possible embodiment of the invention, the numerals 1 and 2 designate upper and lower plates which are arranged in a superposed and substantial parallel relation. The two plates are similar in size and design and each of the plates has a skeleton formation so that air can circulate through the same. By reference to Figure 1, it will be observed that each of the plates is formed with a channel shaped rib 3 which is reversely curved back and forth throughout the length of the plate, thereby providing a series of alternately disposed and oppositely opening loops *a* which are substantially in the shape of horse shoes. At the ends of the plates the channel shaped rib 3 is curved to provide closed loops *b*, the extremities of the channel shaped rib intersecting the curved portions of the adjacent open or horse shoe shaped loops *a*. The ribs 3 have both the upper and lower faces thereof channelled, so that the upper and lower plates 1 and 2 are interchangeable, and the looped portions *a* and *b* of the channel shaped rib are connected by suitable stiffening webs 4, while the peripheral portions of the plates are constituted by frames 5 of which the edge portions are shown as curved downwardly. 75

Interposed between the upper and lower plates 1 and 2 are the reversely disposed rolls 6 of the sheet metal thicknesses between which the resistance element 7 is positioned. Each of the sheet metal thicknesses 6 has a lining 8 of insulating material so that the resistance element 7 which zigzags back and forth is properly insulated and kept out of contact with the sheet metal. The two sheet metal plates 6 with the insulating layers 8 and resistance wires 7 fitted between the same are bent back and forth to provide the reversely disposed rolls *c* which correspond to the reversely disposed loops *a* of the channel shaped ribs 3 of the upper and lower plates 1 and 2. The edge portions of these sheet

metal thicknesses 6 are received within the channel shaped ribs 3 of the plates 1 and 2, and the parts are held rigidly in an assembled position by means of tie bolts 9 which connect the plates 1 and 2 and extend through certain of the open rolls *c* of the thicknesses 6. The end portions of these thicknesses 6 are bent to provide closed rolls which correspond to the closed end loops *b* 10 of the channels 3, and the extremities of the sheet metal thicknesses are thus brought into engagement with adjacent rolls 3 so that the insulating material and resistance element are housed and protected at these 15 points.

The lower plate 2 is provided at the corners thereof with legs 10 by means of which the heater as a unit may be supported in an elevated position. These legs may be 20 of any conventional construction, being shown as secured at their upper ends to the frame 5 of the lower plate 2 by fastening bolts 11.

The resistance element 7 is preferably in 25 the form of a crimped wire, as shown, which has a suitable composition so that it will be heated to the proper temperature when an electric current of the proper voltage is permitted to pass through the same. The two 30 extremities of the resistance element are secured to binding posts 12 which are fitted into notches 20 in an extension 13 of one of the end stiffening webs 4 of the lower plate 2. Electric current is supplied to the 35 heater through a conventional flexible cable 14 which passes through an insulating sleeve 15 in one end of the lower plate 2 and has the terminals thereof secured to the binding posts 12 and thereby placed in electrical 40 connection with the resistance wires 7. These binding posts 12 are housed within one of the closed end rolls of the upright thicknesses so that they are effectively shielded and protected against coming into 45 contact with any exterior object.

When the heater is in operation the resistance wires 7 will be heated by the passage of the electric current through the same. The heat from the resistance wires will be 50 transmitted to the sheet metal thicknesses 6, and owing to the reversely rolled formation of these thicknesses a large heating surface or area is provided. Not only is there a large surface provided for the radiation 55 of heat, but the skeleton construction of the upper and lower plates and the open spaces between the upright rolls provide in an effective manner for convection air currents. A very efficient heater is thus provided, and 60 it will be obvious that the peculiar construction enables the parts to be assembled without difficulty and without the necessity of providing a large number of fastening members. The insulating layers 8 and resistance wires 7 are positioned between the

two sheet metal thicknesses 6 while the latter are in a flat condition, after which the assembled thicknesses with the resistance element between the same are reversely bent to provide the rolls *c*. The upper and 70 lower edge portions of the rolls are received within the channels 3 of the upper and lower plates so that all of the parts are held rigidly in proper position by means of the tie bolts 9. 75

The asbestos layers or thicknesses 8 are preferably treated with some suitable chemical substance such as a solution of silicate of soda or water glass for the purpose of causing them to become good conductors of 80 heat without destroying their insulating properties for electricity.

While I have illustrated and described one particular embodiment of the invention, it will be obvious that many changes and 85 modifications can be made in the details of construction without departing from the fundamental and underlying idea of the invention.

Having thus described my invention what 90 I claim as new is:—

1. A heater including opposed plates having corresponding channels therein, sheets having edge portions thereof received within the channels, means connecting the opposed plates to hold the parts in an assembled relation, and heating means between the sheets. 95

2. A heater including opposed plates provided with channel shaped ribs having corresponding configurations, sheets interposed between the plates with edge portions thereof received within the channel ribs, tie means connecting the plates, and heating means between the sheets. 100

3. A heater including opposed plates provided with channel shaped ribs which extend back and forth in similar configurations on the two plates, sheets extending edgewise between the plates and bent back and forth so that edge portions thereof are received within the channels, tie means connecting the plates, and an insulated resistance member between the sheets. 110

4. A heater including opposed plates provided with channel shaped ribs which extend back and forth across the plates to provide corresponding intermediate loops and have the extremities thereof returned to provide closed end loops, sheets extending between 115 the opposed plates and having the intermediate portions thereof bent back and forth while the end portions are looped so that edge portions of the sheets are received within the channel shaped ribs, and an insulated 120 resistance element arranged between the sheets. 125

5. A heater including similar and interchangeable opposed plates provided with ribs having channels on opposite sides there- 130

of and arranged in corresponding configurations on the two plates, sheets extending between the plates and bent so that edge portions thereof are received within the channelled ribs of the plates, tie means connecting the plates, and an insulated element between the sheets.

6. A heater including upper and lower skeleton plates arranged in an opposed relation, sheets extending between the plates and bent to provide a plurality of rolls, tie means connecting the plates for clamping the sheets between the same, and a resistance element between the sheets.

15 7. An electric heater including a pair of metal sheets, a resistance confined between the sheets, and means having a detachable interlocking engagement with the edges of the sheets to hold the parts in assembled relation.

8. An electric heater including a pair of metal sheets, a resistance confined between the sheets, and plates engaging edge portions of the sheets and interlocking there-
25 with to hold the parts in assembled relation.

9. An electric heater including a pair of metal sheets, a resistance confined between the sheets, and plates having channelled portions which receive edges of the sheets to hold the parts in assembled relation.

30 10. An electric heater including a pair of metal sheets, a resistance confined between the sheets, said sheets having end portions thereof returned to protect the exposed edges of the sheets at the ends thereof, and opposed plates engaging the remaining edges of the sheets to protect the same and hold the parts in assembled relation.

11. An electric heater including a pair of 40 metal sheets, a resistance confined between the sheets, said sheets having the ends thereof returned to protect the exposed end edges of the sheets, and opposed plates having channelled portions receiving the remaining edge portions of the sheets to protect the same and hold the parts in an assembled relation.

50 12. An electric heater including a pair of rectangular metal sheets which are of the same size, a resistance confined between the sheets, said sheets being reversely bent back and forth to provide oppositely opening loops extending transversely thereof and the extremities of the sheets being returned to protect the end edges thereof, and opposed plates provided with channelled portions which receive the edges of the sheets at the sides thereof to protect the said edges and hold the parts in an assembled relation.

60 13. An electric heater including a pair of opposed metal sheets, a sheet of insulating material applied to the inner face of each metal sheet, and a resistance element closely confined between the metal sheets, said re-
65 sistance element being directly engaged by

the insulating sheets and held in position thereby.

14. An electric heater including a pair of opposed metal sheets, a sheet of insulating material applied to the inner face of each of 70 the metal sheets, and a resistance wire zig-zagged back and forth between the metal sheets and closely confined between the same, said resistance wire being in direct engagement with the sheets of insulating material 75 and being held in proper position thereby.

15. An electric heater including a pair of opposed metal sheets which are reversely bent back and forth to provide oppositely 80 opening loops extending transversely thereof, a sheet of insulating material applied to the inner face of each of the sheets, a resistance element closely confined between the metal sheets and directly engaged by the insulating sheets, and means engaging the 85 metal sheets to hold the parts in an assembled relation.

16. An electric heater including a pair of opposed rectangular metal sheets which are reversely bent back and forth to provide 90 oppositely opening loops extending transversely thereof, sheets of insulating material applied to the inner faces of the metal sheets, a resistance wire zig-zagged back and forth between the metal sheets and closely confined between the same, said resistance wire being directly engaged by the sheets of insulating material and held in position thereby, and end plates engaging edge portions 95 of the metal sheets to hold the parts in an 100 assembled relation.

17. An electric heater including interchangeable upper and lower plates arranged in an opposed relation, sheets extending between the plates and engaged thereby to 105 hold them in operative position, and a resistance element confined between the sheets.

18. An electric heater including upper and lower plates arranged in an opposed relation, sheets having edge portions thereof in 110 engagement with the plates and bent to provide a plurality of rolls, and a resistance element closely confined between the sheets.

19. An electric heater including a pair of opposed sheets arranged in a substantially 115 upright position, an insulated resistance element closely confined between the sheets, and upper and lower transversely disposed skeleton plates associated with the upright sheets, the skeleton formation of the plates 120 facilitating the movement of convection currents at the sides of the sheets.

20. An electric heater including a pair of substantially upright sheets, an insulated resistance element closely confined between the 125 upright sheets, said sheets having substantially vertical bends therein which provide upright air channels, and upper and lower transversely disposed skeleton plates associated with the sheets, and the skeleton for- 130

mation of the plates cooperating with the upright channels of the sheets to facilitate the movement of convection air currents.

21. An electric heater including a pair of 5 opposed upright sheets, an insulated resistance element closely confined between the upright sheets, said upright sheets being reversely bent back and forth to provide upright channels, and upper and lower trans-

versely disposed plates associated with the sheets, one of the plates having a skeleton formation and the openings therein registering with the upright channels of the sheets to facilitate the movement of convection air currents.

In testimony whereof I affix my signature.

WILLIS W. HALE.
